Primary Examiner — Cynthia Ramirez*Assistant Examiner* — Michael A Maharajh*(74) Attorney, Agent, or Firm* — Danton K. Mak(57) **CLAIM**

The ornamental design of a massager, as shown and described.

DESCRIPTION

FIG. 1 is a perspective view of a massager showing my new design;

FIG. 2 is a right side front elevational view thereof;

FIG. 3 is a rear elevational view thereof;

FIG. 4 is a left side elevational view, the right side being a mirror image thereof;

FIG. 5 is a top view of the massager of FIG. 1 thereof; and, FIG. 6 is a bottom elevation view thereof.

The broken lines shown in the drawings are for the purpose of illustrating environment structure and form no part of the claimed design.

1 Claim, 5 Drawing Sheets(56)
